[57] CLAIM

The ornamental design for a dispenser for paper roll or the like, as shown and described.

DESCRIPTION

FIG. 1 is a perspective view of a dispenser for paper roll or the like showing our new design;

FIG. 2 is a reduced side elevational view taken from the left of FIG. 1;

FIG. 3 is a reduced top plan view thereof;

FIG. 4 is a reduced front elevational view thereof.

The undisclosed rear is plain and unornamented.

FIG. 1

FIG. 2

FIG. 3

FIG. 4
